ATTACHMENT FOR WRITING MACHINES

John Q. Sherman, Dayton, Ohio

Application April 21, 1933, Serial No. 667,210

3 Claims. (Cl. 197—6)

This invention relates to an accessory for typewriters and analogous writing machines whereby the written material may be indented or physically impressed in the writing material sheet by 5 scoring or by breaking the fiber of the paper or other writing material so that the writing pigment will penetrate more deeply and thereby produce an indelible record. The invention pertains to an improved means for applying the 10 "check protector" idea to material written upon a typewriter. It has heretofore been proposed to sheathe the platen roll of a typewriter with an enclosure having a roughened surface by which the written material is indented, which, however, 15 at all times retains its position relative to the writing material and the platen. Acknowledgment is also made of prior attempts to utilize rotary discs of carbon or transfer material for man- ifolding written records.

20 Differing, however, from both of these prior endeavors, the present invention involves the use of an underlying body of material having a roughened surface, the configurations of which are to be impressed in the writing material, and con- 25 tinuously and automatically effecting relative shifting movement of the sheet of writing mate- rial and the underlying roughened material during the writing process whereby the surface config- 30urations of the latter may be reproduced in the writing material in progressively changing posi- tions.

The object of the invention is to improve the construction as well as the means and mode of 35 operation of indelibly impressing written matter in a sheet of paper or other writing material, whereby such means and apparatus will not only be simple and cheap in construction, but it will be more efficient in use, automatic in operation, applicable to ordinary typewriters now in use, un- 40 likely to get out of repair, and quickly movable into and out of writing position.

A further object of the invention is to provide 45 an indenting or scoring means applicable to ordinary typewriters which may produce a pro- gressively changing configuration of the protec- tive indentations or scorings which will be distinc- tive in appearance and exceedingly difficult to 50 counterfeit, and to provide a vertically and later- ally adjustable support therefor.

55 A further object of the invention is to provide an indenting or scoring device which may be so cheaply produced as to permit it to be discarded after being used a few times, thereby insuring clean, sharp and deep markings upon successive written areas.

A further object of the invention is to provide a suitable and convenient supporting means for the indenting or scoring device upon which such devices are quickly and easily interchangeable.

A further object of the invention is to provide 5 a device embodying the desirable features and characteristics hereinafter set forth.

With the above primary and other incidental objects in view, as will more fully appear in the specification, the invention consists of the features of construction, the parts and combinations thereof, and the mode of operation, or their equivalents, as hereinafter described and set forth in the claims.

Referring to the accompanying drawing, 15 wherein is shown the preferred, but obviously not necessarily the only form of embodiment of the invention, Fig. 1 is a front elevation of a popular style of typewriter to which the present invention has been applied and showing the indenting or scoring disc and its support associated therewith. Fig. 2 is a detail sectional view illustrating the re- 20 lation of the indenting or scoring device to the platen roll, the paper and the imprinting type of the typewriter. Fig. 3 is a detail view illustrating 25 the detachable mounting of the indenting or scoring device. Fig. 4 is an enlarged detail sectional view.

Like parts are indicated by similar characters of reference throughout the several views.

Referring to the drawing, 1 is a writing machine 30 having a platen roll 2 about which a sheet of paper or other writing material 3 is progressively fed past a writing position where it is subject to the impact of the writing machine type bars 4, against 35 an overlying inked ribbon, as is customary, by which pigment is transferred to the struck area, as is the usual practice.

It has long been the practice to fill in the amount upon a check by indenting or scoring the 40 area of the letters and figures, thus enabling the ink to penetrate into the body of the check and prevent the erasure of the written amount. Such protective feature is provided in check writing machines by use of special type having corru- 45 gated or indented faces. It is frequently desirable to fill in checks upon a typewriter or other writing machine and also equally desirable to write or fill in legal documents and other records by indelibly impressing the written matter there- 50 in. The present invention provides a simple and inexpensive means for achieving such results upon an ordinary typewriter, the type of which have not been specially prepared for such purpose.

To this end, there is provided in the present in- 55

stance a rotary disc 5 of relatively hard but preferably flexible material which is operatively positioned behind the sheet of paper or other writing material intermediate such sheet and the platen 5 roll 2 with its peripheral margin gripped therebetween. In practice this indenting or scoring disc 5 has been made of hard rubber, the surface of which is sharply corrugated. Such hard rubber disc possesses a reasonable degree of flexibility and yet it presents a hard, unyielding, sharp toothed surface against which the typewriter type 4 impinge, forcibly impressing the writing sheet 3 against the disc and indenting or scoring the surface of the letter imprinted thereon. The surface configuration of the disc may comprise parallel straight V-shaped corrugations, as are shown in the drawing, or such roughened surface may comprise circular or spiral corrugations, or it may consist of a criss-cross design or a design of irregular configuration. Whatever the design may be, the constant rotation of the disc as the writing progresses presents this embossed design in progressively changing position. For example, employing the parallel straight corrugations, illustrated in the drawing, one written letter may have such lines horizontal while the next will be slightly inclined and each succeeding letter further inclined toward the vertical until finally the letter is written whereon the indented or scored lines are substantially vertical, and thereafter each succeeding letter will have its score lines inclined progressively in reverse direction until again they assume horizontal relation. Obviously many intricate, pleasing and effective designs may be produced by varying the surface configurations of the disc.

The disc 5 is supported coincident with the writing position of the machine and with its peripheral margin gripped between the writing 40 sheet and platen roll and the tangential point thereof, by a supporting arm 7 carrying at its end a pivotal stud 8 engaging a central hole in the disc 5 which is thereby mounted for rotary motion. The pivotal mounting stud 8 is preferably provided with a laterally extending lip or flange 9 which serves to temporarily retain the disc 5 in position upon the stud, but does not interfere with nor prevent quick removal and replacement. The arm 7 is provided with a serrated, segmental head 10, the periphery of which is provided with ratchet teeth 11. This head 10 is pivoted at 12 to an adjustable carrier or bracket 13 slidingly adjustable vertically upon a standard 14 to which it is secured in its adjusted position by the set screw 15. A pawl 16, upon the bracket or carrier 13, engages the peripheral ratchet teeth of the segmental head to hold the disc supporting arm 7 in any one of numerous positions of adjustment. The supporting standard 14 is laterally adjustable relative to the typewriter 1 to present the embossing or scoring disc 5 in proper relation to the writing position. As the writing operation progresses, the travel of the platen carriage, and with it the platen roll 2 and record sheet 3, transmits to the pivotally mounted disc 5 a rotary motion about the stud 8 due to the frictional engagement of the peripheral portion of the disc with the writing sheet and platen roll. Such rotary motion of the disc presents the surface corrugations thereof in constantly changing relation with the record sheet 3, thereby varying the impressed design of succeeding letters and figures, or not, depending upon the design of the corrugations.

75 To the contrary, the design of the corrugations

may be so arranged on the disc that succeeding portions will always be presented in the same relative position at the writing point. In any event the rotation of the disc presents a different working area to receive each succeeding impression. By vertical adjustment of the disc supporting arm, different concentric areas of the disc may be presented in operating position until the entire surface of the disc has been utilized and by further upward movement it may be adjusted to inoperative position, as desired. 5

While for illustrative purposes the invention has been illustrated and described as a rotary disc, it is to be understood that the embossing element may comprise other forms than disc-like and in lieu of having a rotary travel movement past writing position in unison with the reciprocatory movement of the platen, such embossing element may be mounted for lineal travel in unison with the platen or may be connected 15 for reciprocation in unison therewith. 20

Likewise the embossing material carried by the supporting arm need not be movable during use. Rotary motion, while desirable, is not essential. 25

While a pawl and ratchet adjustment for the supporting arm is illustrated, it is obvious that a tight frictional joint or interengaging clutch faces upon the connecting parts will be effective. Since such connections are well known and form no part per se of the invention they have not 30 been illustrated.

When making manifold copies, wherein only the original writing is to be protected, or when the multiple copies are so thick that the embossed impression is ineffective through all the copies, the material may be first written in the usual manner without using the embossing device and then by adjustment of the supporting arm the embossing disc may be dropped behind the uppermost sheet only, which is the original writing, and the matter may then be rewritten thus effecting the protective imprinting or embossing in the original writing only and also double inking the protected writing. 35 40 45

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages. 50

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims. 55 60 65 70 75

Having thus described my invention, I claim:

1. As an article of manufacture, a relatively hard flexible disc having parallel corrugations, said disc being centrally perforated for revolvably mounting upon a support, and adapted to be positioned behind a record sheet to receive the pressure of the writing operation whereby the corrugated surface of the disc will be impressed in the record sheet, but in progressively different angular relation. 70 75

2. Embossing means for use with a writing machine wherein a section of roughened material is to be positioned behind a sheet of record material being inscribed in the writing machine, characterized by a support therefor including an arm on which the roughened material is carried, a ratchet head upon said arm, a carrier to which the arm is pivoted, and a pawl on the carrier engaging with the ratchet head to hold the arm in any one of numerous different positions of adjustment.

3. Embossing means for use with a writing ma-

chine wherein a section of roughened material is to be positioned behind a sheet of record material being inscribed in the writing machine, characterized by a support therefor including an arm on which the roughened material is carried, a carrier to which the arm is pivoted, said carrier being adjustable both vertically and horizontally relative to the writing machine, and means for releasably holding the arm in any one of several positions of pivotal adjustment relative to the carrier.

JOHN Q. SHERMAN.
